UNITED STATES PATENT OFFICE.

ALFRED CURRIE, OF DELHI, NEW YORK.

ICE-CUTTING MACHINE.

1,104,634.

Specification of Letters Patent. Patented July 21, 1914.

Application filed June 11, 1913. Serial No. 773,034.

To all whom it may concern:

Be it known that I, ALFRED CURRIE, citizen of the United States, residing at Delhi, in the county of Delaware and State of New York, have invented certain new and useful Improvements in Ice-Cutting Machines, of which the following is a specification.

The present invention relates to certain new and useful improvements in ice cutting machines, and more particularly to that type of ice cutters in which the cutters are driven by a motor which is also adapted to be employed for propelling the frame upon which the cutters are mounted.

Among the objects of the invention is to provide an ice cutting machine which embodies novel features of construction whereby the machine can be moved forward and backward at the will of the operator, and also whereby the cutters and other parts used in the cutting of the ice can be raised into an inoperative position when the machine is traveling over ordinary ground and is not in operation.

A further object of the invention is to provide novel and improved means for raising the cutting saws and adjusting them to any desired elevation so as to cut a certain depth into the ice.

A further object of the invention is to provide adjustable guides or markers which are hinged to the sides of the main frame of the machine and enable the operator to gage with accuracy the size of the cakes of ice that are being cut.

In connection with the foregoing, it will be observed that the construction of this machine is such that the frame which carries the engine and cutting equipment does not have to be raised from the surface of the ice in order to elevate the saws above the ice.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a front elevation of an ice cutter and tractor constructed in accordance with the invention. Fig. 2 is a top plan view

of the same with the rear portion of the operator's platform and seat removed to show the mechanism beneath. Fig. 3 is a side elevation of the same. Fig. 4 is a detail perspective view showing the method of mounting the saws, and Fig. 5 is a detail perspective view of a portion of one of the guide boards, showing the manner of mounting the same for adjustment.

Corresponding and like parts are referred to in the following description and indicated in all the views of the drawings by the same reference characters.

Specifically describing the present embodiment of the invention, the numeral 1 designates the main frame of the ice cutter, the said frame being pointed at its forward end as indicated at 2, and being braced at its rear end by the cross piece 3. At the extreme rear end of the frame upright standards 4 and 5 are provided, the said standards being located upon opposite sides of the frame. The forward end of the machine may be provided with the platform 6 and operator's seat 7.

The motive power for the machine may be furnished by a gasoline engine 8 which is shown as mounted upon a platform 8^a extending transversely of the main frame 1 at the rear of the forward platform 6. A suitable fuel supply tank 9 is provided for holding the gasoline for feeding the engine. The shaft 11 of the engine 8 is disposed transversely with respect to the ice cutter, one end of the shaft being provided with a tooth or sprocket wheel 10, while the opposite end of the shaft is journaled within a suitable bearing 12 and projects laterally beyond the side of the frame 1, the extremity of the shaft having a pulley 13 applied thereto. This pulley 13 is belted to a second pulley 14 upon a counter-shaft 15 which is suitably journaled upon the frame 1. From this counter-shaft 15 power is transmitted to the drive shaft 16 through the medium of a short longitudinal shaft 16^a and bevel gearing 16^b.

A suitable clutch mechanism 15^a is mounted upon the counter-shaft 15 for throwing the drive shaft 16 into and out of operation and reversing the direction of rotation thereof. A suitable lever C is provided for controlling this clutch mechanism 15^a.

The drive shaft 16 is provided with a sprocket wheel 17^a which is connected by 110

a chain 17^b to a sprocket wheel 17^c upon a tractor shaft 17 which is journaled between the side pieces of the frame toward the rear end thereof. Opposite ends of the 5 tractor shaft 17 are provided with the traction wheels 18 which are adapted to be driven in either direction to propel the machine either forwardly or rearwardly over the surface of the ice. The pointed 10 forward end 2 of the main frame is provided with a vertical shaft 19^a which has a forked lower end 19^b within which a steering wheel 19 is mounted. The upper end of the vertical shaft 19^a is provided 15 with a suitable handle 20 by means of which the said shaft can be rotated and the steering wheel 19 turned laterally for the purpose of directing the movement of the ice cutter either to the right or to the left. 20 Both the clutch lever C and the steering handle 20 are located adjacent the seat 7 at the forward end of the machine so that the operator can control the movements of the machine without leaving his seat. 25 Mounted upon the respective standards 5 and 4 at the rear end of the machine are the vertical guide rods 21 upon which the saw shaft boxes 22 and 23 are slidably mounted. These boxes 22 and 23 provide 30 bearings for the saw shaft 24 the ends of which project laterally beyond the said bearing boxes and are threaded to receive the jam nuts 25 and 26 between which the circular saw cutters 27 are clamped. Suitably located on the shaft 24 is a sprocket 28 which is connected to the toothed fly wheel 10 of the engine 8 by the chain 29. In order that the bearing boxes 22 and 23 can be raised and lowered upon the vertical 35 guide rods 21 for the purpose of adjusting the elevation of the saws, there is provided a rock shaft 30 which is journaled between the standards 4 and 5. Rigid with this shaft 30 is a bell crank lever 31 and an 40 arm 32, the said bell crank lever and arm being applied to the shaft toward opposite ends thereof. The arm 31^a of the bell crank lever is connected by a link 33 to an eye 22^a extending from the side of the box 22, while the arm 32 is connected by a similar 45 link 34 to a corresponding eye 23^a projecting from the side of the box 23. The opposite arm of the bell crank lever 31 is connected by a link 35 to a hand lever H which is mounted upon the operator's platform 6 at the forward end of the machine, thus making it possible for an operator sitting upon the seat 7 to raise and lower the saw shaft 24 by manipulating the lever H. 50 It will be observed that the said rock shaft 30 is sufficiently high upon the standards 4 and 5 to provide for a proper clearance of the chain 29 under all conditions, and that the cross piece 3 of the frame I is 55 cut away as at 3^a to admit of the chain. 60

running without interference when the shaft 24 is at its lowest position. As previously stated, the end portions of the saw shaft 24 are threaded from the boxes 22 and 23 all the way to the tips or extremities thereof and project some distance beyond the sides of the frame I, thereby making it possible to obtain a lateral adjustment of the cutters 27 in addition to the vertical adjustment. 70

Each side of the main frame or carriage 75 I is provided with a guide board 36 which is disposed longitudinally of the frame and parallel to the side bar thereof, the said guide boards being adjustably mounted upon lateral arms 37 which are hinged as at 39 to the frame and mounted to swing in a vertical plane to admit of the guide boards being raised and lowered. By reference to Fig. 5 it will be seen that these swinging arms 37 are each provided with a series of 80 perforations 37^a adapted to receive the pins 36^a, one of the pins being located upon each side of the guide board 36 and the said pins being adapted to be fitted into any selected 85 openings according to the position of the guide board upon the swinging arm. Suitable diagonal braces 40 are provided between the swinging arms 37 upon each side of the frame, and with this construction it will be 90 obvious that the guide boards 36 can be adjusted in and out upon the arms 37 and can be swung upwardly into an inoperative position when not in use. With further reference to these guide boards it will be observed that the same are held in an elevated 95 position by means of the hooks 37^b secured to the sides of the frame I, which are adapted to engage with suitable eyes 37^c carried by the bars 37. 100

In the operation of the device, the machine is driven to the ice field with the cutters 27 and guide boards 36 raised into an inoperative position. When the ice field is reached, the cutters 27 are lowered into engagement with the ice and the machine then 105 caused to be propelled across the ice in the desired direction so as to make a cut of the desired width and depth the full length of the field. The cutters are then raised, the machine turned around, and one of the guide 110 boards 36 lowered into engagement with one of the cuts made by the cutter on its first trip. The cutters are then again lowered and the machine driven back across the ice field to make a cut as before, the lowered 115 guide board 36 sliding in one of the previous cuts so as to insure that the second strip of ice will be cut parallel to the first strip. This operation is repeated until the entire ice field is covered, the guide boards always being maintained in engagement with one of the previous cuts so that the various strips of ice will all be parallel to each other and accurately cut to the desired size. 120

Having thus described the invention, what 125 130

I claim as new and desire to secure by Letters Patent, is:—

1. An ice cutting machine including a carriage, standards on said carriage, a motor mounted upon the carriage, traction wheels driven by said motor, guide rods applied to the before mentioned standards, journal boxes slidably mounted upon the said guide rods, a shaft journaled in the said boxes, rotary cutters upon the shaft, a driving connection between the shaft and the motor, and means for sliding the journal boxes upon the guide rods to adjust the cutters. 10
  2. An ice cutting machine including a carriage, means for propelling the carriage, standards projecting from the carriage upon opposite sides thereof, a guide rod secured to each standard, journal boxes slidably mounted upon the guide rods, a cutter shaft journaled in the journal boxes, cutters applied to the cutter shaft, a rock shaft journaled between the standards, an operative connection between the rock shaft and the journal boxes, and means for operating the rock shaft to slide the journal boxes upon the guide rods and adjust the rotary cutters. 20
  3. An ice cutting machine including a carriage, standards projecting from the carriage, guide rods secured to the standards, journal boxes slidably mounted upon the 30
- guide rods, a cutter shaft mounted within the journal boxes and having opposite ends thereof threaded, rotary cutters adjustably fitted upon the threaded ends of the cutter shaft, clamping nuts threaded upon the ends 35 of the shaft and engaging the rotary cutters to hold the said cutters securely in adjusted positions, and means for moving the journal boxes upon the guide rods to raise and lower the cutters. 40
4. An ice cutting machine including a carriage, means for propelling the carriage, a pair of standards projecting from the carriage at the rear end thereof, a guide rod secured to each of the standards, journal boxes 45 slidable upon the guide rods, a cutter shaft mounted in the journal boxes, cutters upon the cutter shaft, a rock shaft journaled between the standards, an operative connection between the rock shaft and the journal boxes, 50 a hand lever at the forward end of the carriage, and an operative connection between the said hand lever and the rock shaft.

In testimony whereof I affix my signature in presence of two witnesses.

ALFRED CURRIE.
